FIG 5

FIG 2

UNITED STATES PATENT OFFICE.

ADELMER M. BATES AND ALBERT KRASA, OF CHICAGO, ILLINOIS, ASSIGNEES TO BATES VALVE BAG COMPANY, OF CHICAGO, ILLINOIS, A CORPORATION OF WEST VIRGINIA.

TRIMMER FOR SEWING MACHINES.

Application filed January 26, 1924. Serial No. 688,725.

To all whom it may concern:

Be it known that we, ADELMER M. BATES and ALBERT KRASA, citizens of the United States, and residents of Chicago, in the 5 county of Cook and State of Illinois, have invented a new and useful Trimmer for Sewing Machines, which invention is fully set forth in the following specification.

Our invention relates to a trimmer for 10 sewing machines and has for its object to provide such a trimmer which can be readily applied to one of the usual types of sewing machines. Our trimmer is particularly adapted to be applied to such a sewing machine as disclosed in the patent for sewing machine granted to Dudley S. Seymour July 6, 1915, No. 1,145,620, although it might be applied with obvious changes to other machines.

20 Referring to the drawings forming a part of this specification,

Fig. 1 is a side elevation of a sewing machine with our trimmer applied, parts being in section along the line 1-1 of Fig. 2. 25 Fig. 2 is a front elevation partly in section along the line 2-2 of Fig. 1. Fig. 3 is a section showing the operative connection of our trimmer to the main shaft of the machine, and shows these parts along the line 30 3-3 of Fig. 1. Fig. 4 is a section on the line 4-4 of Fig. 2. Fig. 5 is a detail showing the relation of the tape feeders to the needle.

35 The feeding and seam-forming parts of the sewing machine are shown in the drawings as being constructed in the same way as the similar parts of the machine described in the above cited patent.

40 A standard 11 supports an overhanging arm 12 in the end of which there slides a needle bar 13, carrying a needle 14. The needle bar operating lever 15 is connected by a link 16 to an eccentric on the main shaft 17. The main shaft runs through a tubular work support 18. A looper 19 adapted to co-operate 45 with the needle is operated by a carrier 20 and reciprocated by a link 21 connected to the needle operating lever 15. The looper carrying bracket 22 is mounted on a rock shaft 23, which is rocked by a fork 24 embracing an eccentric on the main shaft 17.

A feed dog 25 is mounted on an arm of a frame 26. The frame 26 is pivoted to a rock frame 27, which in turn is mounted upon a pivot 28, supported in brackets 29. The 55 feeding movement of the feed dog is caused by a connection with the main shaft, which operates the rock frame 27. This connection is not shown in the drawings and may be formed in any suitable manner, for example, in the way disclosed in the above cited patent.

The vertical movement of the feed dog is caused by a link 31 which connects a pivot pin 32, mounted in the frame 26, to a pivot 65 pin 33 on the arm of a rock shaft, not shown. This rock shaft may be operated in any suitable manner, for example, like the corresponding rock shaft in the above cited patent.

70 The above described parts form no part of our invention and may be constructed in any suitable manner. They are disclosed merely to indicate the manner in which our trimmer may be attached to this type of sewing machine.

75 Our trimmer consists in a cutter plate 40 and its operating mechanism. The plate reciprocates in a slot 41 in the presser foot 42 and through a registering slot in the throat plate 43. The plate is fastened by a screw 44 to a knife carrying slide 45, which reciprocates in a guide 46. The knife guide 46 is pivoted at 47 to a lug 48, extending from a bracket 49. The pivot rod 50, by 80 which the frame 26 is pivoted to the frame 27, is extended at the front end of the machine, as at 51. This extension is connected by a link 52 to a pivot pin 53 in the knife guide 46. In this way, the knife guide 85 is oscillated about its pivot 47, giving the knife substantially co-incident movement with the horizontal movement of the feed dog.

85 The bracket plate 49 is fastened in any suitable manner to the under side of the tubular work support 18. Lugs 54 depending from the plate 49 support a rock shaft 55. An arm 56 of this rock shaft is connected by a link 57 to an eccentric 58 upon 100 the main shaft 17. Another arm 49 projects from the front end of the rock shaft

55 and is connected by a link 60 to the slide 45, and thus the reciprocatory movement of the knife 40 is controlled by the eccentric 58.

56 A guide 61 projects from the entrance end of the presser foot for guiding material beneath the foot. The guide 61 is provided with a slot 62 extending from about midway of its upper surface to a point on its lower surface just in front of the needle 10 and in line with a groove 63, which ends backward beneath the needle.

57 A tape 64 may be guided to the entrance of opening 65, a guide 65. This guide is shown with a quarter turn at 66, from which 45 the main part 67 of the guide extends to any suitable source of supply for the tape. It is more convenient to have the tape some distance back from the front of the machine so as to avoid any interference with the 50 manipulation of the work, but it is desirable to guide the tape into the slot 62 without any turn between the end of the guide and the slot, and for this reason the quarter turn 66 is interposed in the guide.

58 A similar guiding opening 68 is provided in the throat plate and forms an extension of the guide 69 for a tape 70, which is fed through the throat plate and beneath the needle.

59 The operation of the mechanism thus far described is as follows:

60 The operation of the main part of the sewing machine forms no part of our invention and is the same as described in the 35 above cited patent and needs no further description. We prefer to guide tape to the work on each side in line with the needle so as to form a re-inforced seam, but this is not necessary for the use of our trimmer. 40 The feed dog reciprocates in the direction of feed and also to and from the work. It will be readily seen that as the material is fed forward intermittently beneath the needle, the knife moves forward with the 45 material, as the forward and backward motion of the knife is simultaneous with that of the feed dog; but the vertical motion of the knife is independent of that of the feed dog. The timing of the vertical reciprocation of the knife is such as to cause it to be drawn downward during the return movement of the feed dog and while the knife is moving against the stationary fabric. This 55 gives the knife a drawing cut across the fabric. The operation of the knife is improved by the slight inclination of its top end towards the on-coming fabric, as clearly shown in Fig. 2.

60 As will be seen, the trimmer can be applied to the sewing machine with no change in the regular parts of the machine and with very simple additions which may be attached to the outside of the tubular work support, only the link 57 extending through 65 the wall of the work support into operative

relation with an eccentric on the main shaft.

66 The knife-operating parts are readily accessible by removing the guard plate 71, supported by bracket 72 from a downward extension 73 on the lug 54. This plate is held in position by means of a spring 74, attached to the bracket 49 and adapted to catch beneath the bracket 72.

70 Variations in the trimmer may be made within the scope of the appended claims 75 without departing from the spirit of the invention.

75 What we claim is:

1. In a sewing machine, a substantially L-shaped guide pivoted at the end of one of its arms, a carrier slidable longitudinally of the other arm of the guide, a cutter mounted in the carrier beyond the end of said other arm, means to oscillate the guide, and means to reciprocate the carrier. 80

2. In a sewing machine, a knife, a carrier for the knife, a guide for the carrier pivoted near the end of the carrier distant from the fabric, means for oscillating the guide and means for reciprocating the carrier longitudinally of the guide. 85

3. In a sewing machine, having a main shaft, a knife, a carrier for the knife, a guide for the carrier pivoted to a stationary portion of the machine frame, a connection between the guide and the main shaft for rocking the guide upon its pivot and a separate connection for reciprocating the carrier within the guide. 90

4. In a sewing machine having a main 100 shaft and a feed dog, a trimming knife positioned transversely of the movement of the material, a carrier for the knife, means connected to the main shaft for reciprocating the carrier, a guide for the carrier and means connecting the guide to the feed dog operating means for oscillating the guide transversely of the carrier. 105

5. In a sewing machine, a cutting knife, a carrier for the knife, a guide for the carrier pivoted to a stationary portion of the frame, a feed dog and means to give it a feeding movement, and means to connect the feeding means to the guide between the pivot and the knife. 110

6. In a sewing machine, a cutting knife, a carrier for the knife, a guide for the carrier pivoted to a stationary portion of the frame, a feed dog and means to give it a feeding movement, means to connect the feeding means to the guide between the pivot and the knife and means to reciprocate the carrier within the guide. 115

7. In a sewing machine, a substantially L-shaped guide pivoted at the end of one of its arms, a carrier slidable longitudinally of the other arm of the guide, a cutter mounted on the carrier beyond the end of said other arm, a feed dog, means to operate the feed dog, connections between said operating 120

means and the guide, and separate means for reciprocating the carrier in the guide.

8. In a sewing machine, a feed dog, means to move the feed dog to and from the work, means to reciprocate the feed dog in the direction of movement of the work, a knife mounted separately from the feed dog, connections between the last said means and the knife for reciprocating the knife simultaneously with the feed dog in the direction of travel of the work, and separate means for reciprocating the knife transversely of the work.

9. A cutter adapted to be attached to a sewing machine having a tubular work support and a main shaft within said support, comprising a bracket adapted to be attached to the under side of the work support, a knife guide pivoted to the bracket, means for oscillating the guide on its pivot, a knife-carrier slidably mounted in the guide, and operative means adapted to connect an eccentric on the main shaft of the sewing machine with the carrier.

10. A cutter adapted to be attached to a sewing machine having a tubular work support, comprising a knife, means beyond the end of the mechanism in the work support for reciprocating the knife in the direction of travel of the work, and means outside of the work support and connected to a link actuated by an eccentric on the main shaft

for reciprocating the knife transversely of the work.

11. In a sewing machine, a tubular work support, a main shaft extending longitudinally within the support and a feed dog for advancing the work, a knife extending across the path of the work, a bracket fixed to the bottom of the work support, a guide pivoted on the bracket, a carrier for the knife slidably mounted in the guide, a link connecting the feed dog carrier to the top end of the guide, a rock shaft mounted in the bracket and having one arm connected to the slide and another arm connected to a link extending through the wall of the work support into operative relation with an eccentric on the shaft.

12. In a sewing machine having a main shaft and a feed dog, a trimming knife positioned transversely of the movement of the material, a carrier for the knife, means connected to the main shaft for reciprocating the carrier, a guide for the carrier, operating means for the feed dog, and a link substantially parallel with the direction of travel of the work and connecting the feed dog operating means to said guide.

In testimony whereof we have hereunto subscribed our names to this specification.

ADELMER M. BATES.
ALBERT KRASA.
